ELECTROLYTIC CONDENSER

Philip Dubiller, New York, N. Y., assignor to
 Nova Electric Corporation, New York, N. Y.,
 a corporation of New York

Application April 18, 1936, Serial No. 75,039

4 Claims. (Cl. 175—315)

My invention relates to wet electrolytic condensers and more particularly relates to novel multi-section wet electrolytic condenser construction within a common container.

5 There are many applications for high capacity multi-section condensers, particularly in the radio art. A multi-section condenser having a common negative terminal has heretofore been limited to the so-called dry electrolytic condensers where the positive foil sections were independently wound upon a common concentric condenser section. The advantages of wet electrolytic condensers over the dry electrolytic condensers reside in a longer life, lower power factor 10 and no break-down or puncturing of the electrodes.

I contemplate a dual or multi-section wet electrolytic condenser construction having a relatively large capacity and correspondingly small 20 space. A common structural mounting assembly for the condenser results in a material economy in assembling the unit in a radio chassis. In accordance with my present invention, a corrugated, etched aluminum section comprises the 25 positive electrode for each condenser section. A metallic spacer is used to isolate each condenser section to eliminate intercapacity coupling between the condenser sections as well as increase their capacitance and reduce their 30 power factor. The corrugated, etched condenser elements are provided with perforations or holes to further increase the section capacitance as will hereinafter be described.

It is accordingly an object of my invention to 35 provide novel wet electrolytic multi-section condenser constructions.

Another object of my invention is to provide novel multi-section wet electrolytic condensers of increased capacitance per unit volume.

40 A further object of my invention is to provide novel multi-section wet electrolytic condensers free of intersection capacitance.

These and other objects of my invention will 45 become apparent in the following description in connection with the drawing in which:

Figure 1 is a partial cross-sectional elevation taken through a preferred construction of a dual electrolytic condenser in accordance with my present invention.

50 Figure 2 is a cross-sectional view taken along 2—2 of Figure 1 illustrating the isolated dual section condenser construction.

Figure 3 shows a partial section of the perforated aluminum sheet comprising the condenser 55 sections.

Figure 4 is a modification illustrating a triple section wet electrolytic condenser.

Referring to Figure 1, metallic container 10 is preferably of cylindrical shape and generally made of aluminum. The top section 11 has an annular shoulder 12 and contains a suitable breather construction which is not shown to permit escape of rapidly formed gases. Container 10 has an externally threaded boss 13 at the opposite end. Boss 13 is conically bored to receive 10 an insulation stopper 14. Member 14 is preferably a resilient rubber stopper which is press fit into boss 13 to suitably seal the liquid electrolyte 15 within container 10. The ends 16 of boss 13 are pinched to firmly secure stopper 14 in position. A nut 17 is adapted to co-act with the threads 18 of boss 13 to suitably mount the electrolytic condenser upon a chassis in a well known manner.

The container 10 forms a common condenser 20 terminal and electrical connection to the common terminal is generally made through the chassis attachment construction including boss 13, nut 17 and the bottom of container 10. The positive elements 19 and 20 of the dual condenser 25 are vertically supported by rods 21 and 22. The liquid electrolyte 15 entirely surrounds condenser sections 19 and 20 and communicates between sections at the top portion 15' above metallic spacer 23. Electrolyte 15 may be any suitable liquid or viscous electrolyte for example a solution of borax and boric acid. Spacer 23 is a metallic partition, preferably welded at the ends 30 24 and 25 to container 10 as clearly illustrated in Figure 2 and is of the same material as container 10.

Figure 2 illustrates the semi-circular corrugated form of condenser sections 19 and 20 of the dual condenser modification, on their supporting posts 21 and 22. The upper portions of rods 21 and 40 22 are flattened to facilitate riveting together of the ends of the sections 19 and 20 thereon with rivets 26. The pitch and width of the corrugations of sheets 19 and 20 may be used to provide a maximum non-interfering, exposed 45 surface.

To provide a maximum capacitance per unit volume of the electrolytic condenser, the aluminum foil sections 19 and 20 are constructed in the following manner: The aluminum sheet 27 50 partially illustrated in Figure 3 is used to build up the positive sections 19 and 20 of the electrolytic condenser. The sheet is first etched in a well known manner to increase the active surface of the section. Perforations 28 are then 55

made in the sheet for reasons to be explained hereinafter. The aluminum sheet 27 is then pre-formed in a manner well known to those skilled in the art. The next step is to corrugate the aluminum sheet in the manner illustrated in Figure 2. It is then formed in a semi-circular form and riveted to the supporting posts 21 and 22 as already described.

The positive sections are inserted into the container 10 and the metallic rods 21 and 22 project through corresponding holes in the rubber stopper 14 to serve as electrical connection terminals therefor. Lugs 29 and 30 are attached to the ends of terminal rods 21 and 22 for suitable connection thereto. The metallic spacer 23 has originally been welded or secured in position between the dual condenser sections 19 and 20. The bottom end 23' of shield 23 is preferably inserted in a corresponding groove in rubber stopper 14 although this expedient is not essential.

Metallic shield 23 is at the same potential as the negative container 10 and accordingly shields the individual capacitance sections 19 and 20 to avoid interelectrode capacitance therebetween as will be understood by those skilled in the art. Another advantage of the shield 23 is that it increases the capacitance of either condenser section due to the effective capacitive relation between the adjacent sections 19 and 20 and the plate 23. Provision of perforations 28 which incidentally have not been illustrated in Figures 1 and 2 in order to simplify the drawing, permit capacitive interactions of the internal portion of the semi-circular sections 19 and 20 with the surface of surrounding container 10 and in my present invention, also of shield 23 in a well known manner.

It will now be evident that the multi-section wet electrolytic condenser construction in accordance with my present invention provides for a maximum capacitance within a given volume or space and avoids intercapacitive action between the sections to accordingly electrically isolate them except for the common negative terminal. The provision of corrugated, perforated, etched aluminum foil permits a maximum capacitive efficiency for a given condenser section volume.

Figure 4 illustrates a modification of the hereinabove described dual condenser sections comprising three sections 31, 32 and 33 corresponding to the dual sections 19 and 20. Sections 31-32-33 are similarly mounted on connection posts 34, 35 and 36 which communicate to the exterior of the container 10 for terminal connections to the respective sections as will now be understood. Suitable metal spacers 23a are welded into container 10 and as illustrated in Figure 4 may be readily constructed by bending one sheet 37 at its center at an angle of 120° and welding another sheet thereto at 38. It is to be understood that more than three sections may be built up into a single condenser container in a manner similar to the already described modifications.

Although I have illustrated a preferred construction for the novel multi-section wet electrolytic condensers, it will be evident to those skilled in the art, that modifications may be made that come within the broader spirit and scope of my present invention, for example, the electrolyte may be viscous instead of fluid, and that the spacers 23 may be of insulation mate-

rial or even omitted, and accordingly, I do not intend to be limited except as set forth in the following claims.

I claim:

1. A multi-section electrolytic condenser comprising a metallic container having an opening centrally thereof substantially narrower in diameter than the diameter of the container and adapted for single-opening panel mounting, an electrolyte in the container, a stopper for said opening, a plurality of condenser electrodes, individual closely spaced lead-in rods for said electrodes anchored in said stopper and projecting into said container, said electrodes having cross-sections in the form of a sector of a circle, and being secured to said rods along sector axis portions thereof to form individual centrally supported electrolytic sections coating with the common potential metallic container. 5

2. A multi-section electrolytic condenser comprising a metallic container having an opening centrally thereof substantially narrower in diameter than the diameter of the container and adapted for single-opening panel mounting, an electrolyte in the container, a stopper for said opening, a plurality of condenser electrodes, individual closely spaced lead-in rods for said electrodes anchored in said stopper and projecting into said container, said electrodes having cross-sections in the form of a sector of a circle and 15 being symmetrically arranged about the axis of said container, said sector-shaped electrodes being secured to said rods along sector axis portions thereof to form individual centrally supported electrolytic sections coating with the common potential metallic container. 20

3. A multi-section electrolytic condenser comprising a metallic container having an opening centrally thereof substantially narrower in diameter than the diameter of the container and 25

adapted for single-opening panel mounting, an electrolyte in the container, a stopper for said opening, a plurality of condenser electrodes, individual closely spaced lead-in rods for said electrodes anchored in said stopper and projecting into said container, said electrodes having cross-sections in the form of a sector of a circle and 30 being symmetrically arranged about the axis of said container, said sector-shaped electrodes being secured to said rods along sector axis portions thereof to form individual centrally supported electrolytic sections coating with the common potential metallic container. 35

4. A multi-section electrolytic condenser comprising a metallic container having an opening centrally thereof substantially narrower in diameter than the diameter of the container and 40 adapted for single-opening panel mounting, an electrolyte in the container, a stopper for said opening, a plurality of condenser electrodes, individual closely spaced lead-in rods for said electrodes anchored in said stopper and projecting into said container, said electrodes being secured to said rods at commonly opposing surface portions of the electrodes on the outer periphery thereof and being symmetrically arranged about the axis of said container to form individual centrally supported electrolytic sections coating with the common potential metallic container. 45

5. A multi-section electrolytic condenser comprising a metallic container having an opening centrally thereof substantially narrower in diameter than the diameter of the container and 50

adapted for single-opening panel mounting, an electrolyte in the container, a stopper for said opening, a plurality of condenser electrodes, individual closely spaced lead-in rods for said electrodes anchored in said stopper and projecting into said container, said electrodes being tubular and having cross-sections in the form of a sector of a circle and being symmetrically arranged about the axis of said container, the sector angles of said electrodes totalling within three-hundred and sixty degrees, said sector-shaped electrodes being secured to said rods along sector axis portions thereof to form individual centrally supported electrolytic sections 55 coating with the common potential metallic container. 60

PHILIP DUBILIER.
